UNITED STATES PATENT OFFICE.

PEDER T. PEDERSON, OF VIENNA, SOUTH DAKOTA.

TOY PISTOL.

1,159,706.

Specification of Letters Patent.

Patented Nov. 9, 1915.

Application filed March 17, 1915. Serial No. 15,100.

To all whom it may concern:

Be it known that I, PEDER T. PEDERSON, a citizen of the United States, residing at Vienna, in the county of Clark and State of 5 South Dakota, have invented certain new and useful Improvements in Toy Pistols; and I do hereby declare the following to be a full, clear, and exact description of the invention, such as will enable others skilled in the 10 art to which it appertains to make and use the same.

This invention relates to spring toy pistols for propelling peas or other small projectiles; and it consists in the novel construction and combination of the parts herein-after fully described and claimed.

In the drawings, Figure 1 is a side view of a pistol constructed according to this invention, and showing it discharged. Fig. 20 2 is a plan view of the same. Fig. 3 is a side view of the pistol with one half of its body portion removed, and showing the plunger retracted.

The body portion of the pistol is formed 25 of two similar halves 2 and 3 having a longitudinal joint down the center of the pistol. These two halves are alike, except that one of them, only, has a trigger guard 13 formed on or secured to it, and that they are 30 formed right and left. These halves are formed of light metal, or any other suitable material.

The pistol has a barrel 4 at its front end, a spring chamber 5 at its rear end, a guide 6 at and below the level of the rear end of the barrel, a slot or opening 7 at its top between the barrel and the spring chamber, and a slot or opening 8 between the rear end of the guide 6 and the spring chamber. All of 40 these parts are in halves, corresponding to the respective halves 2 and 3 of the body portion. The pistol has a suitable handle 10 below the spring chamber, also formed in halves, and the halves are secured together 45 by rivets 11.

A plunger or piston 12 is loosely slidable in the barrel, and it has a block 14 at its rear end which slides in the slot 7 at the top of the pistol and projects a little above 50 its top. This block slides in contact with the guide 6, and its bottom portion is free to enter the slot 8 when retracted and pushed downwardly.

A helical coiled spring 15 is arranged in the spring chamber and abuts against its rear end. The front end portion of the spring 15 engages with a projection 16 on the block 14. The trigger 17 is pivoted in the slot 8 on a pin 18, and it has a trip cam or projection 20 at its upper part. 60

The plunger is retracted against the pressure of the spring by the hand of the operator, the projecting part of the block being pushed back. When the block arrives at the rear end of its travel the downward pressure of the fingers forces the block into engagement with the slot 8, and the front bottom corner of the block is held by the shoulder 21 at the rear end of the guide. The spring bends a little laterally and holds the 70 block in this position the bottom side of the spring chamber being inclined downwardly and forwardly to accommodate the spring. When the trigger is pulled, the cam or projection 20 raises the block, so that it and the 75 plunger are projected forwardly by the spring to discharge the projectile. The block with the plunger and the spring are placed in the body portion of the pistol before its two halves are riveted together. 80

What I claim is:

In a toy pistol, a body portion formed of two similar halves secured together and having a central longitudinal joint, said body portion having a barrel at its front end, a 85 spring chamber at its rear end, and a rectangular guideway open at its top side and arranged between the barrel and spring chamber and having a slot and a shoulder at its lower part; a plunger slidable in a barrel 90 and having a rectangular block at its rear end which slides in the said guideway and projects at the top thereof and engages with the said slot and shoulder when retracted and pressed downwardly, a spring arranged in 95 the spring chamber and bearing against the said block, and a trigger pivoted in the said slot and adapted to release the block from the said shoulder.

In testimony whereof I have affixed my 100 signature in the presence of two witnesses.

PEDER T. PEDERSON.

Witnesses:

AUGUST ULSON,
J. BENJ. BRASLIE.
